UNITED STATES PATENT OFFICE.

CHARLES HENRY AUGUSTUS FREDERICK LOCKHART ROSS, OF BALNAGOWN CASTLE,
COUNTY OF ROSS, SCOTLAND.

DRILLING-MACHINE.

1,125,181.

Specification of Letters Patent.

Patented Jan. 19, 1915.

Application filed July 3, 1913. Serial No. 777,344.

To all whom it may concern:

Be it known that I, CHARLES HENRY AUGUSTUS FREDERICK LOCKHART Ross, a subject of the King of Great Britain, residing 5 at Balnagown Castle, county of Ross, Scotland, have invented certain new and useful Improvements in Drilling-Machines; and I do hereby declare the following to be a full, clear, and exact description of the invention, 10 such as will enable others skilled in the art to which it appertains to make and use the same.

This invention relates to drilling machines especially adapted for forming the 15 bores in gun barrels, and has for its object to provide a machine of this character which will be simple in construction, certain in operation, and more efficient in action than those heretofore proposed.

20 With these and other objects in view, the invention consists in the novel details of construction and combinations of parts more fully hereinafter disclosed and particularly pointed out in the claims.

25 Referring to the accompanying drawings forming a part of this specification, in which like numerals designate like parts in all the views:—Figure 1 is a side elevational view of a machine made in accordance with my 30 invention comprising four drill spindles; Fig. 2 is an end elevational view of the parts shown in Fig. 1; Fig. 3 is a sectional view taken on the line 3—3 of Fig. 1; Fig. 4 is a sectional view taken on the line 4—4 of Fig. 35 1; Fig. 5 is a sectional view taken on the line 5—5 of Fig. 1; Fig. 6 is a sectional detail view of the means for readily clamping in position the rods attached to the chip-hoods; Fig. 7 is an elevational view partly 40 in perspective of the means for controlling the connection between a tail stock and its feed screw; Fig. 8 is an end elevational view partly in section of the parts shown in Fig. 7, and also illustrating the guide rods 45 between which the tail stock rests; Fig. 9 is a longitudinal sectional view of the parts, shown in Fig. 7; Fig. 10 is a cross sectional view of the parts shown in Fig. 9; Fig. 11 is a longitudinal view taken through a head stock, the corresponding transmitting mechanism, and its associated parts; Fig. 12 is a cross sectional view of the parts shown in Fig. 11, and also illustrating the guide rods 50 between which the head stock is clamped; Fig. 13 is a cross sectional view illustrating

certain portions of the tail stock and the automatic means associated therewith for cutting off the power when the friction between the drill and work becomes too great; Fig. 14 is a diagrammatic plan view showing a portion of the mechanism illustrated in Fig. 13; and, Fig. 15 is a diagrammatic sectional view of one of the chip-hoods illustrating the work, the hollow drill, and its associated parts.

1 indicates any suitable framework provided with the end standards or members 2, between which extends the guide rods 3, 4, 5, 6 and 7, associated with each of which are the feed screws 8, 9, 10, and 11 respectively. The said feed screws are further respectively provided with the beveled gears 12, 13, 14 and 15, which in turn respectively mesh with the beveled gears 16, 17, 18 and 19, carried by the readily adjustable stud shafts 20 on which are mounted the curved slotted members 21 coacting with the bolt and nut mechanism 22 adapted to secure the said shafts 20 in any angular position to which the slots 23 may be adjusted, as will 50 be readily understood. Also mounted on the stud shafts 20 are the gears 24 adapted to mesh with the worms 25 carried by the shafts 26 on which are mounted the gears 27 meshing with the pinions 28, mounted upon 55 the driving shafts 29, each carrying fast and loose pulleys 30 and 31 respectively, all as will be clear from Figs. 1, 2 and 11. Coacting with the fast and loose pulleys 30 and 31 are the power belts 32 associated 60 with the automatic bell shifters 33 to be mentioned below.

From what has now been disclosed, it will be clear that power may be transmitted from the pulley 31 through the power shafts 29, 95 the pinions 28, the gears 27, and the above described connecting mechanism to the feed screws 8, 9, 10, etc. It will also be clear that by adjusting the curved slotted members 21, the said stud shafts 20 may be readily so 100 turned as to disengage or separate the gear 24 from its corresponding worm 25, and therefore, the particular feed screw associated with said gear 24, may be readily cut out.

105 Referring now more particularly to Figs. 1 and 3, it will be observed that the guide rods numbered from 3 to 7 are associated with a sectional member 35 forming a sort of bed plate or strip, and that the various 110

head stocks 36 are provided with integral extensions 37, which are bolted to said bed plate or strip 35, as by the means 38, so as to firmly secure said head stocks to the frame-work of the machine. The feed screws 6 pass through this bed plate or strip, as illustrated, and the said head stocks, as well as the strip-like member 35, are supported from the guide rods 3, 4, 5, 6 and 7. Also 10 supported upon the said guide rods are a plurality of tail stocks 40, as will be clear from Fig. 5. Further, between the tail stocks and the head stocks are located a plurality of chiphoods 42 (see Figs. 1 and 15) each provided with a cover 43, and with bushings 44 and 48, through which the hollow drill 45 passes, as well as with a bushing 46 adapted to support the end of the work, or gun barrel, 47. The bushing 46, as 20 well as the bushing 48, is preferably supported in a sleeve 49, which in turn is associated with a bearing 50 rigid with the chiphood 42, all as will be clear from Fig. 15.

25 The purpose of the construction just described, is to permit the gun barrel, or work, 47 to readily rotate in the bearing 50, while the drill 45 may remain stationary, but also to permit the drill 45 to in turn rotate when 30 the friction between the said gun barrel and drill exceed a certain amount, all as will be more clearly disclosed below.

As will be clear from Figs. 1, 3 and 6, the axes of the work 47 are in prolongation of 35 the axes of the various driving shafts 29, and that the said work pieces 47 are held by the head stocks and revolved through the driving shafts by means of any suitable and well known connections, such as 55. It, 40 accordingly, follows that as power is applied through the belts 32, the power shafts 29 are revolved, as well as the work pieces 47.

The drill spindles 45 are secured to their respective tail stocks by any suitable and 45 well known means, such for example as the tubular members 56, shown in Figs. 4, 5, 13 and 14, and they may be secured in said tubular members by friction or other means not shown. The said drill spindles are further normally held against rotation by 50 means of the projecting members 57 taking against the projecting members 58 carried by the rods 59 provided with the springs 64, all as will be now more clearly 55 disclosed. That is to say, on the chucks or tail stock connections, I preferably provide cam members such as 57, see Figs. 5 and 13, adapted to coact with lever-like projections 58 carried by the shafts 59 extending parallel to the supporting rods numbered from 60 3 to 7 and also extending from their respective tail stocks to their respective head stocks, as will be clear from Figs. 5 and 11, 12, 13 and 14. The purpose of the cams 65 57, rods 59, and coacting parts is to auto-

matically cut off the power when the friction between the point of the drill 45 and the work exceeds a certain amount, and the means by which this is accomplished will now be described.

Referring more particularly to Fig. 15, it will be readily understood that since the drill member 45 is held stationary in the tail stock, and since the barrel or work 47 is constantly rotating, it is evident that the 75 friction might, under certain conditions, become so great as to destructively strain the drill spindle 45. In order to prevent this result, I employ any suitable and well known means such as the tubular members 80 56, the cam members 57 and the projections 58, which will hold the drill spindles 45 against rotation until a predetermined strain is experienced; the parts being so arranged that the said member 56 will rotate 85 and carry with it the cam 57 which in turn will, through the lever member 58, rotate the shaft 59 when said strain is exceeded. The rotation of this shaft will in turn rotate the lever-like projection 60 carried by the shaft 90 59 (see Fig. 11) and raise it out of contact with the shoulder 61 and permit the said projection 60 to slide along the slot 62 with which the lug 63 mounted on the head stock 95 36 is provided.

The movement of the lug 60 in the slot 62 is accomplished by means of the spring 64, which surrounds the shaft 59 and takes against the head stock 36 at one end and the collar 65 at the other end. This said spring, 100 in other words, slides the shaft 59 longitudinally, and in thus moving the said shaft, it also moves the belt shipper 33 and carries the belt 32 from the fast pulley 31 on to the loose pulley 30, all as will be clear from said Fig. 11.

The shifting of the belt, as just described, of course, cuts off power from the work, as well as from its corresponding feed screw, and of course stops the drilling operation. 110 The handle 66 with which the shaft 59 is also provided enables the operator to move the said shaft 59 against the action of the spring 64, and therefore restore all the parts to their normal positions. In addition to 115 the above mechanism, there is disclosed in Figs. 13 and 14, a curved or beveled lug or projection 66' adapted, as the tail stock 40 advances, to contact with the cam-like stop 120 lever 67 with which the shaft 59 is also provided and to turn said lever 67 and shaft 59, as will now appear. This stop lever 67 is adjustable along the shaft 59, and its object is to provide an automatic means by 125 which the feeding movement of the tail stock may be stopped whenever the drill spindle 45 has bored a predetermined distance. Accordingly, when the members 66 and 67 come into contact the curved end of the member 66' strikes the lever 67 and 130

turns it together with the shaft 59, whereupon, the shaft 59 is rotated on its axis, as above disclosed, and the belt shipper 33 moves the power belt from the power pulley 31 to the idle pulley 30, and therefore stops the drilling operation.

It will be understood, of course, that the work 47, as best illustrated in Fig. 15, freely rotates, and that this action is facilitated 10 by the bushing 46, and the sleeve 49 in which is mounted the bushing 48. The rotation of the drill spindle 45 is further facilitated by means of the bushing 44, which freely rotates within the boring provided by the 15 hood 42.

It is, of course, desirable to adjust the chiphoods 42 to and from the head stocks 36, and to firmly hold them in their adjusted positions in order to accommodate different 20 lengths of work pieces. To accomplish this purpose, each of the hoods 42 is provided with a rod 70 rigid with the hood at one end, and the other end adapted to freely slide through apertures in the different 25 head stocks 36, as will be clear from Figs. 1 and 6. The said head stocks 36, however, are provided with a plug 71 and a piston 72 between which the said rod 70 passes. The piston 72 is adapted to be readily 30 controlled by means of fluid under pressure in the pipe 73, which pipe in turn is controlled by the valve 74, associated with the fluid outlet 75, see Fig. 6.

It will now be clear from what has just 35 been said, that the chiphoods 42 and their associated rods 70, may be freely adjusted to and from the head stocks 36, whereupon a turning of the valve 74 will admit fluid under pressure above the piston 72, which 40 will cause the latter to firmly clamp the rod 70 and its associated chiphood in its adjusted position. A turning of the valve 74 in the opposite direction will permit the fluid to escape through the pipe 75, and 45 thereupon release the clamping action of the piston 72, whereupon the chiphood may be adjusted to a new position.

The drill spindle 45 is provided with a bore 76 adapted to constantly feed oil to 50 the tip of the spindle, and thereby keep the latter well lubricated during the drilling operation. This oil is preferably supplied under pressure to each drill spindle through a pipe 80, which communicates with the 55 passage 81 (see Fig. 9), which passage is controlled by the longitudinally movable valve 82 provided with the by-pass 83. The said passage 81 further communicates with the branch passage 82' leading to the passage 83' in the tail stock which registers with the passage 76 in the drill spindle 45, all as will be clear from Fig. 9. When, 60 however, the valve 82 is raised into the position shown in said figure, oil will be cut off from the drill spindle. Also controlling

the passage 81 is the valve 85 provided with a by-pass 86, and an exhaust passage 87 leading to the atmosphere. When the said valve 85 is so moved as to cause its by-pass 86 to register with the passage 81, then oil 70 will be fed into the sleeve 88 and above the piston 89 located in said sleeve, and having the extension or piston rod 90 associated therewith. To the rod 90 is attached at one end the sleeve 91 having the friction 75 surface 92 adapted to engage the corresponding friction cone 93 with which the sleeve 88 is provided. The said sleeve 88 is rigidly secured as at 94 to the tail stock 40, and therefore, does not move. To the piston 98, however, is secured the worm 30 wheel 95 adapted to engage the feed screw 8, and also adapted to move up and down with said piston 89 a slight distance without disengaging said feed screw. Accordingly, when the by-pass 86 is so positioned as to admit oil to the piston 89, the said piston moves downwardly, as seen in Fig. 9, and jams the surfaces 92 and 93 together, so that the gear 95 can not turn, 90 owing to the fact that the sleeve 91 is rigidly secured to the rod 90 by the spline 100. The gear 95 not being able to turn, and yet still being in mesh with the threads of the feed screw 8, it will act as a nut toward the 95 feed screw 8 and the latter will therefore feed the tail stock 40 forward. On the other hand, if the valve 85 is raised into the position shown in Fig. 9, so as to cut off the oil from the piston 89, the friction between the surfaces 92 and 93 will be released, as will presently appear, and the gear 95 will turn freely so that the feed screw 8 will not in that case move the tail stock 40. 105

The means by which the friction between the surfaces 92 and 93 is released is as follows:—A passage 101 connects the passage 81 with the by-pass 86 and the exhaust 87 when the valve 85 is in the position shown 110 in Fig. 9, and therefore, the pressure which formerly existed upon the piston 89, is released, which accordingly, permits the surface 92 to rotate relative to the surface 93. The rod 90 is further provided with the hand wheel 105 through which the tail stock 115 may be readily manipulated. That is to say, the rotation of the gear 95 may be prevented by holding the hand wheel 105 against rotation, and the tail stock thus be compelled to be fed along by the feed screw 8 even though oil is cut off from the piston 89. By turning the hand wheel 105 in the opposite direction, the tail stock may be of course, readily likewise moved in an opposite direction. The valve 85 is provided with a head 106 which overlaps the head 107 with which the valve 82 is provided, and therefore, when the valve 85 is depressed, it further causes the valve 82 to be depressed. 120 125 130

4
 The effect of this action is to compel oil to be fed to the passages 82, 83 and 76, or to the drill spindle whenever the gear 95 is moved downward and the tail stock is being fed toward the work. That is to say, the overlapping of the head 107 by the head 106 prevents the drilling operation, except when oil is being fed to the drill point, while, of course, the mechanism is also such that the tail stock can be freely manipulated as in other cases.

The operation will be clear from the foregoing, but may be briefly summarized as follows:—Power being applied through a belt, such as 32, the shaft 29 is rotated and transmits power through gears 28, 27, 25 and 24 to the shaft 20 and through the gears 16 and 12 to one of the feed screws, such as 8. The shaft 29 also will turn the work 47, which may be a gun barrel, one end of which is supported in a chuck such as 55, and the other end of which is supported in the rotatable member 46 mounted in the rotatable sleeve 49, which in turn is mounted in the bearing 50 with which the chiphood 42 is provided. The hollow drill spindle 45 rests in the rotatable members 44 and 48, and therefore, permit the said spindle to be normally stationary, while the work revolves, but to also rotate when the friction between the work and the point of the spindle exceeds a predetermined amount. The spindle 45 is carried by the chuck 56 with which the tail stock 40 is provided, and when the friction between the spindle and work becomes excessive, the said chuck 56 will revolve, rotate the cam 57, the lever 58, and the shaft 59, which in turn will rotate the lever dog 60 thereby disengaging the same from the shoulder 61 and permitting it to longitudinally slide in the slot 62 under the action of the spring 64, and thereby move the belt shipper 33 to the left, as seen in Fig. 11, and also the power belt from the fast pulley 31 to the loose pulley 30, thereby cutting off power from the work and feed screw. Further, as the tail stock 40 is fed forward by the feed screw 8, a projection 66 carried by the chuck 56 comes in contact with an adjustable stop 67, carried by the shaft 59 and rotates the said stop and shaft in the manner just described, so as to likewise cut off power from the work and feed screw. By adjusting the stop 67 along the shaft 59, the drill point can be made to automatically stop drilling, after having bored a predetermined distance, even though the friction may not have become excessive. The head stocks 36 are rigidly secured to the framework, and in order to adjust the chiphoods 42 and to fix them at the proper distances from the said head stocks, the said chiphoods are provided with the adjustable rods 70, which may be clamped to the head stocks, as best illustrated in Fig. 6, by means

of fluid supplied by the pipe 73, controlled by the cock 74 and acting against the piston 72.

In order to feed the tail stocks toward the work, oil under pressure is admitted through the channel 81 under the control of the valves 82 and 85 to the piston 89, which jams down the conical surface 92 against the surface 93, and thereby locks the gear 95 against rotation. When thus incapable of rotating, the said gear 95 acts as a nut and causes the tail stock 40 to be fed toward the work by the feed screw 8, all as will be clear from Fig. 9.

In order to insure that the tail stock and drill may not be fed forward unless oil is admitted to the channel 76 of the drill, the valve head 107 of the valve 82 is overlapped by the valve head 106 of the valve 85 so that oil cannot be admitted to the piston 89 and the tail stock fed forward, unless the channel 82' leading to the passage 76 is open for the admission of oil to the drill point. When oil is not admitted to the piston 89, on the other hand, then the surface 92 is not jammed against the surface 93 and the gear 95 turns freely with the spindle 90, and therefore, the tail stock is not fed forwardly. It accordingly results from the structure now disclosed, that the tail stock may be automatically fed forward, or it may be fed forward and backward by manipulating the handle 105.

I have shown four drill spindles adapted to simultaneously act upon four pieces of work, but of course, it is evident that any number of spindles may be provided.

It is obvious that those skilled in the art may vary the details of construction, as well as the arrangements of parts, without departing from the spirit of my invention, and therefore, I do not wish to be limited to the above disclosure, except as may be required by the claims.

What I claim is:—

1. In a drilling machine the combination of a plurality of power shafts; a plurality of feed screws; independent connections between each power shaft and each feed screw; a plurality of head stocks through which said power shafts pass; a plurality of guide rods on which said head stocks rest; a member associated with said guide rods through which said feed screws pass; means for clamping said member to said head stocks; means for rotatably supporting one end of the work; means for rotatably supporting the other end of the work; a normally non-rotatable drill spindle rotatably supported by said last mentioned means; and means for feeding said spindle from said feed screw, substantially as described.

2. In a drilling machine the combination of a plurality of power shafts; a plurality of feed screws connected to said shafts; a

plurality of head stocks provided with extensions; a plurality of guide rods for supporting said extensions; a strip like member clamped to said guide rods and extensions through which said feed screws pass; means carried by each power shaft for rotatably supporting one end of each work piece; a plurality of rotatable means for rotatably supporting the other end of each work piece; a connecting member between each head stock and each of said last named supporting means; and a plurality of drill spindles supported by said last named rotatable supporting means adapted to simultaneously contact with said work pieces, substantially as described.

3. In a drilling machine the combination of three or more supporting rods; three or more head stocks adjustably supported on said rods; three or more chip hoods provided with rotatable supporting means for the work pieces and drill spindles; a rod connecting each chip hood and head stock; a clamping means carried by each head stock for adjustably securing the same to its corresponding rod; and a strip located beneath said supporting rods to which each head stock is clamped; substantially as described.

4. In a drilling machine the combination of a plurality of supporting rods; end standards between which said rods are secured; a plurality of independent head stocks slideable on said rods; a strip associated with said rods for holding said head stocks in position; a chip hood for each head stock; a rod connecting each chip and head stock; a clamp for securing each head stock to said rod; a plurality of normally non-rotatable drill spindles, means carried by each hood for rotatably supporting one end of each spindle; and means associated with each spindle for permitting it to rotate when an abnormal strain is produced; substantially as described.

5. In a drilling machine, the combination of a head stock; a pair of guide rods for supporting said head stock; a tail stock; a chip hood located between said head and tail stocks; a fluid controlled piston on said head stock for adjustably securing said hood to said head stock; a rotatable work support carried by said hood; a rotatable drill support carried by said hood; and means carried by said tail stock for normally holding said drill against rotation, substantially as described.

6. In a drilling machine, the combination of a head stock; a tail stock; a chip hood located between said head and tail stocks; means for adjustably securing said hood to said head stock; a rotatable work support carried by said hood; means for rotatably supporting the work associated with said head stock; a rotatable drill support carried by said hood; means carried by said tail

stock for normally holding said drill against rotation; and means associated with said last mentioned means for cutting off the power of the machine when said drill is rotated, substantially as described.

7. In a drilling machine, the combination of means for rotating the work; means for normally holding the drill against rotation; means for automatically stopping the machine when the drill is rotated; and means for automatically feeding the drill to the work, substantially as described.

8. In a drilling machine, the combination of a tail stock; means associated with said tail stock for normally holding one end of a drilling tool having an oil channel against rotation; means associated with said stock for supplying oil to said channel; means for automatically stopping the machine when the drill begins to rotate; rotatable means for supporting the other end of said tool; and means for rotatably supporting the work in operative relation to said tool, substantially as described.

9. In a drilling machine, the combination of a tail stock; means associated with said tail stock for normally holding one end of a drilling tool having an oil channel against rotation; means associated with said stock for supplying oil to said channel; rotatable means for supporting the other end of said tool; means for rotatably supporting the work in operative relation to said tool; means for automatically feeding the drill to the work; and means for preventing said automatic feed when the passage of oil to said channel is obstructed, substantially as described.

10. In a drilling machine, the combination of a tail stock adapted to hold a drill tool having an oil channel, said tail stock also provided with an oil passage adapted to deliver oil to said channel; means for automatically feeding said tail stock toward the work; means for controlling the supply of oil to said channel; and means coacting with said controlling means adapted to prevent the automatic feeding motion of said tail stock except when said passage is open to allow oil to enter said drill channel, substantially as described.

11. In a tail stock provided with an oil passage, the combination of means for holding a drill tool having an oil channel in an operative relation with the work; a valve controlling said passage; a cylinder with which said passage communicates; and a second valve also controlling said passage as well as said first valve, substantially as described.

12. In a tail stock provided with an oil passage, the combination of means for holding a drill tool having an oil channel in an operative relation with the work; a valve controlling said passage; a cylinder with

- which said passage communicates; a second valve also controlling said passage as well as said first valve; a feed screw; means on said tail stock coating with said feed screw 5 to move said tail stock; and means associated with said cylinder whereby said second mentioned means may be prevented from moving said tail stock, substantially as described.
13. In a tail stock having an oil passage, a valve controlling said passage; a second valve also controlling said passage as well as said first valve; a cylinder with which said passage communicates; a piston in said cylinder; a feed screw; a feed gear carried by said piston coating with said feed screw; and means associated with said piston and gear for preventing the rotation of said feed gear when oil is admitted to said cylinder, substantially as described.
14. In a tail stock having an oil passage, a valve controlling said passage; a second valve also controlling said passage as well as said first valve; a cylinder with which 25 said passage communicates; a piston in said cylinder; a feed screw; a feed gear carried by said piston coating with said feed screw; and means comprising fixed and movable frictional members associated with 30 said piston and gear for preventing the rotation of said feed gear when oil is admitted to said cylinder, substantially as described.
15. In a tail stock provided with an oil 35 passage, the combination of means for holding a hollow drilling tool adapted to be fed from said passage; means for automatically feeding said tail stock toward the work; and means so controlling said feeding means
- and passage as to prevent said tool being 40 moved except when said oil passage is open, substantially as described.
16. In a tail stock provided with an oil 45 passage, the combination of means for holding a drill tool provided with an oil channel, adapted to be fed from said passage; a reciprocating valve controlling said passage; a feed screw for moving said tool toward the work; a connection comprising a fluid controlled piston between said screw 50 and tail stock; a second valve for controlling said piston; and connections between said first and second valves, substantially as described.
17. In a tail stock provided with an oil 55 passage; the combination of a piston adapted to be operated by the oil in said passage; a feed screw; gear connections between said screw and piston; and a frictional connection between said tail stock and piston, substantially as described.
18. In a tail stock provided with an oil 60 passage; the combination of a piston adapted to be operated by the oil in said passage; a feed screw; gear connections between said screw and piston; connections between said tail stock and piston comprising friction surfaces controlled by said piston, a valve 65 controlling said passage; and a hand operated means adapted to operate said piston independently of said valve and passage.

In testimony whereof I affix my signature, in presence of two witnesses.

CHARLES HENRY AUGUSTUS
FREDERICK LOCKHART ROSS.

Witnesses:

W. CAMPBELL,
GEORGE H. BANKES.
